(57) **CLAIM**

The ornamental design for a shower as shown and described.

DESCRIPTION

FIG. 1 is a perspective view of the claimed design; FIG. 2 is a front view of the claimed design shown in FIG. 1; FIG. 3 is a rear view of the claimed design shown in FIG. 1; FIG. 4 is a bottom view of the claimed design shown in FIG. 1; FIG. 5 is a top view of the claimed design shown in FIG. 1; FIG. 6 is a side view of the claimed design shown in FIG. 1; and, FIG. 7 is another side view of the claimed design shown in FIG. 1.

The equal length dashes depict portions of the shower that form no part of the claimed design. The unequal length dashes shown in the figures depict the boundaries of the claim and form no part thereof. The shower is shown with a symbolic break in its length. The appearance of any portion of the article within the break lines forms no part of the claim.

1 Claim, 5 Drawing Sheets
